H. J. REED.
FABRIC CLASP.
APPLICATION FILED MAY 3, 1920.

Patented Jan. 18, 1921.

FIG. 1

FIG. 2

FIG. 4

FIG. 3

Henry J. Reed Inventor

By H. L. & S. L. Reynolds

Attorneys

UNITED STATES PATENT OFFICE.

HENRY J. REED, OF SEATTLE, WASHINGTON.

FABRIC-CLASP.

1,365,850.

Specification of Letters Patent. Patented Jan. 18, 1921.

Application filed May 3, 1920. Serial No. 378,432.

To all whom it may concern:

Be it known that I, HENRY J. REED, a citizen of the United States of America, and resident of the city of Seattle, in the county 5 of King and State of Washington, have invented certain new and useful Improvements in Fabric-Clasps, of which the following is a specification.

This invention consists of a fabric clasp 10 or a device which is designed to be attached to, and to hold fabrics. One of the important uses to which it would be put is, as a hose supporter, but it is, however, not limited to this particular use. It may be employed to engage and hold any kind of 15 fabric.

The object of my invention is to provide a device of this kind which may be adapted for holding, with equal efficiency, heavy and 20 light fabrics, and which will grip such fabric so as to engage a wider part thereof, and which will therefore hold a given amount with less danger of injury to the fabric.

25 In the accompanying specification I will describe the construction and manner of operation of my invention and will then define what I consider to be the novel features and will define those upon which I 30 desire patent protection in the claims terminating the specification.

In the accompanying drawings Figures 1, 2 and 3 show the clasp in various positions, Fig. 1 being the position which the 35 parts occupy when the clasp is about to be applied to the fabric.

Fig. 2 shows the next step in securing the fabric and Fig. 3 the final position of the parts.

40 Fig. 4 is a longitudinal section through the device as applied to a fabric.

I employ as a base frame a member 1, which is herein shown as of skeleton structure and formed of wire bent in substantially 45 a rectangular form. The skeleton structure, while desirable, from a practical standpoint, does not affect the principles of operation of my invention and may therefore be omitted, at least, in certain parts.

50 At one end of this frame means are provided whereby the clasp may be supported or secured to the desired support; the means illustrated consists in forming a loop 10, into which is secured the end of a web 11, by 55 indenting the vertical sides of the frame.

and securing them together at the points of indentation by a clip 12. Any other suitable and desired means for supporting the clasp may be employed. If desired, a short section of tubing 13 may be employed to join 60 the ends of the wire and to form the base upon which the web 11 is secured.

At the opposite end of the frame 1, a cross bar 2 is provided, this should be off-set slightly. In conjunction with the frame 1, 65 I employ two other members, one of them being a loop 3 which is preferably made of wire, and a retaining tongue, or plate 4, herein shown as made of a sheet of metal. Also, these two parts, namely the loop 3 and 70 the retaining plate 4, are secured together so that they may swing, one upon the other; this is shown as secured by forming narrow ears 40, at one side of the plate 4 which are bent about one portion of the loop 3. 75

The hinged end of the retaining plate 4 is provided with a slot 41, which provides a convenient means for securing thereto a retaining web 5, which web is secured about the clip 12, which forms a part of the base 80 frame 1. The chief function of this retaining web 5, is to hold the loop 3 and retaining plate 4, against separation from the frame 1, and also in convenient position for handling, as may be necessary, in securing 85 the fabric. I do not wish to be considered as limited to the use of this particular means for preventing separation of the parts, as other means might be employed for retaining the parts in convenient relationship. 90

The loop 3 is of such size that it may be conveniently passed over the loop formed by the cross bar of the main frame. The retaining plate 4 has its outer end, or the main body thereof, of such width that it 95 may be conveniently entered within the loop formed by the cross bar 2.

The parts of the clasp are caused to assume the position shown in Fig. 1, when it is desired to secure the same to a fabric. 100 This may be conveniently done by engaging the ends of the loop 3 between a thumb and finger. The fabric, of which 6 represents a portion in Figs. 2 ad 3, is then placed upon the frame 1. The loop 3 is then brought 105 down to the position shown in Fig. 2. The connecting member 5, or whatever other means may be employed for securing the parts 3 and 4 to the main frame, must be of such character as to permit movement of 110

the loop 3 to such a point that it may be passed over the loop formed by the cross bar 2 of the main frame.

The loop 3 is then passed over the loop 5 formed by the cross bar 2 and pushed back a sufficient distance that the retaining plate 4 may be passed inside of the bar 2 and below the level thereof. At this point the loop 10 3 and the retaining plate 4 are drawn outward, or down, so as to insert the end of the retaining plate 4 beneath the bar 2, which position is shown in Figs. 3 and 4. The relative length of the loop 3 and the retaining plate 4, should be such that the 15 edge of the retaining plate 4 will lie alongside of, or against the outer bar of the loop 3, when the two are swung together; this condition is clearly shown in Fig. 4.

In the position of the parts described the 20 fabric 6 passes over the outer or lower cross bar of the loop 3, thence over and under the cross bar 2 of the main frame, then under and back of the retaining plate 4. A pull upon the fabric causes a downward pull 25 upon the loop 3; this causes this loop and the retaining plate 4 to swing over against the inner surface of the cross bar 2 and also causes the cross bar of the loop 3 to engage two layers of the fabric between it and the 30 retaining plate 4. The device thus grips the fabric at three separate points. The surface gripped is also of considerable width, being the entire width of the retaining plate 4. Thus a wide area of the fabric is engaged 35 by the clasp and, in consequence, it is much less liable to be torn.

In order to free the clasp from the fabric, the loop 3 is engaged between the finger and thumb and moved upward back of the bar 40 2, until the retaining plate 4 may be swung outward, clear of the cross bar 2. When the retaining plate is thus swung outward the loop 3 is drawn downward, carrying the end 45 of the retaining plate 4 outside of the bar 2, until the loop 3 may be swung beneath and forwardly of the bar 2, in which position the fabric is freed.

It is evident that the details of construction 50 of my invention may be modified in minor ways without, however, affecting the principles employed therein, or the manner of its operation.

What I claim as my invention is:

1. A fabric clasp comprising a base frame 55 having a cross bar at one end laterally displaced from the plane of said frame, a retaining blade and a loop pivoted together, the loop being adapted to pass over the said cross bar of the main frame and the blade 60 to enter the opening between said cross bar and the main body of the frame, and means for connecting the ends of said blade and

the main frame which are distant from the said offset cross bar to permit limited movement lengthwise of the frame. 65

2. A fabric clasp comprising a main frame having at one end a loop which is angularly offset toward one side, a retaining blade and a loop pivoted together along one transversely extending side, the opposite side of the loop being adapted to pass outside of and back of the loop of the main frame and the blade being adapted to enter between the sides of the same frame loop, and a flexible supporting web connecting the opposite end of the main frame and one of the other or retaining members, to permit free movement of the retaining blade and its connected loop to a point which permits the loop to pass over the offset loop of the main 70 frame. 75

3. A fabric clasp comprising a main frame having an angularly offset loop at one end, a fabric holding loop and blade pivoted together and with their swinging edges alongside each other, said latter loop being adapted to pass over the loop of the main frame and the blade to enter within said loop, and means for connecting said parts to permit free movement within limits. 85 90

4. A fabric clasp comprising a main frame having an angularly offset loop at one end, a fabric holding loop and blade pivoted together and with their swinging edges alongside each other, said latter loop being adapted to pass over the loop of the main frame and the blade to enter within said loop, a flexible web connecting the ends of the main frame and the blade which are away from the offset loop of the frame and of a length 100 to permit the holding loop to swing over the said offset loop of the main frame. 105

5. A fabric clasp comprising a main frame of wire formed in substantially a rectangular shape, its vertical sides being indented near their upper ends and the lower side being laterally offset, a clip secured to and joining the lateral sides at the points of indentation, a fabric holding wire loop of substantially rectangular shape, a locking 110 blade pivoted to the upper side of the fabric holding loop, and being perforated at its upper end for the reception of a web, said fabric holding loop being adapted to pass over the laterally offset side of the main 115 frame, and the blade to enter behind said offset side, and a flexible web secured in the perforation in said blade and to said clip, and of a length to permit the fabric holding loop to pass over the laterally offset side of 120 the main frame. 125

Signed at Seattle, Washington, this 27th day of April, 1920.

HENRY J. REED.
